UNITED STATES PATENT OFFICE.

INNOCENT ALBERTELLI, OF CHICAGO, ILLINOIS.

BANANA-CRATE.

No. 862,300.

Specification of Letters Patent. Patented Aug. 6, 1907.

Application filed April 18, 1906. Serial No. 312,399.

To all whom it may concern:

Be it known that I, INNOCENT ALBERTELLI, a citizen of the United States, residing at Chicago, in the county of Cook and State of Illinois, have invented certain new and useful Improvements in Banana-Crates, of which the following is a specification.

My invention relates to banana crates, and has for its object to provide an improved crate in which bananas may be packed for shipment.

10 My invention consists in the combinations and details hereinafter set forth and claimed.

In the accompanying drawings—Figure 1 is a transverse sectional view of my improved crate, showing the parts in operative position. Fig. 2 is a perspective 15 view showing the collapsible body portion. Figs. 3 and 4 are perspective views of the bottom and top rings.

In the drawings *a* represents a cylindrical body portion formed of heavy paper or pasteboard or similar material. The lower end *a'* is inturned and secured 20 to the body portion by any suitable fastening means, such as eyelets *e*. This inturned portion forms a ledge or flange around the inner face of the lower end of the body portion. The upper end of the body portion is folded over outwardly—as indicated at *a''*—and connected in a similar way to the body portion by eyelets *e'*, or by any suitable fastening means. This cylindrical body portion is made from a single sheet of material, having its edges connected together in any suitable manner. I have shown outer and inner cleats *f/f'*

30 extending from top to bottom of the body portion at their meeting edges, these cleats and the edges of the body portion held between them being secured by nails *f''*, or by any suitable fastening means. This body portion, owing to the character of the material of which 35 it is made, is readily collapsible and may be flattened out for the purpose of packing and shipment of the crate.

b is a rigid ring of wood adapted for insertion into the body portion at its upper end, where it frictionally engages the inner face of the body portion and forms a 40 means for distending and holding the upper end of the crate in its operative position. *c* is a similar rigid ring forming the bottom portion, the bottom being formed by cross pieces *c c'* secured to the ring by any suit-

able means—as shown in Fig. 3. This bottom ring is 45 removably held in engagement with the lower inner end face of the body portion and rests upon the ledge or flange formed by the inturned part of the body portion at this lower end—as clearly shown in Fig. 1. By this construction, I provide a bottom portion for the crate 50 which is considerably above the lower end of the crate. The lower inturned end *a'* of the body portion forms a protecting ring and prevents any contact of the bananas with the floor.

Secured to the outer upper edge of the body portion 55 are flaps of flexible material *d*, held at their upper edges between the body portion and its overturned end portion *a''* and secured in position by the rivets *e'* which holds this overturned end portion in engagement with the body. These flaps are adapted to be 60 turned upwardly and tied together, forming a closure for the crate.

The operation of my improved crate will be readily understood. The rings *b* and *c* are inserted into the 65 crate and held in engagement therewith by friction and serve to give the crate its form and hold it in shape. By removing the rings the body portion may be collapsed and the crates packed for shipment in a comparatively small space.

It will be seen that I have provided a very simple 70 and efficient crate, one that may be easily and quickly made at a minimum expense; and one which may be readily put together for use.

I claim:

1. A banana crate, comprising a cylindrical collapsible 75 body portion having its lower end turned inward and secured to the body portion, a removable rigid bottom portion resting on the inturned lower end, and a rigid ring removably engaging the inner face of the upper end of the body portion.

2. A banana crate, comprising a collapsible cylindrical 80 body portion, removable rigid top and bottom portions engaging the inner face of the body portion at its upper and lower ends, respectively, the upper end of the body portion being folded outwardly and secured to the body portion, and flaps of flexible material secured at one edge to the upper end of the body portion.

INNOCENT ALBERTELLI.
